US0D1019540S

(12) **United States Design Patent** (10) Patent No.: **US D1,019,540 S**
(45) Date of Patent: ** Mar. 26, 2024

(54) **RECHARGEABLE BATTERY**

(71) Applicant: **Hixon (Shenzhen) Technology Limited**, Shenzhen (CN)

(72) Inventors: **Xiong Li**, Shenzhen (CN); **Xianlei Yang**, Shenzhen (CN); **Jun Liang**, Shenzhen (CN)

(73) Assignee: **Hixon (Shenzhen) Technology Limited**, Shenzhen (CN)

(**) Term: **15 Years**

(21) Appl. No.: **29/846,002**

(22) Filed: **Jul. 12, 2022**

(51) LOC (14) Cl. **13-02**

(52) U.S. Cl.

USPC **D13/103**

(58) **Field of Classification Search**

USPC D13/102–106, 110, 112, 118, 119, 153,

D13/168, 184, 199; D14/253, 432, 434

CPC H01M 6/00; H01M 6/14; H01M 6/10;

H01M 10/52

See application file for complete search history.

CLAIM

The ornamental design for a rechargeable battery, as shown and described.

DESCRIPTION

FIG. 1 is a perspective view of a rechargeable battery, showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and,

FIG. 8 is an enlarged bottom plan view thereof.

1 Claim, 8 Drawing Sheets
